[57] **CLAIM**

The ornamental design for a locking one-way closure
for disposable containers, substantially as shown.

DESCRIPTION

FIG. 1 is a perspective view of a locking one-way closure
for disposable containers, showing our new design;
FIG. 2 is a top plan view thereof;
FIG. 3 is an underside view thereof;
FIG. 4 is a front elevation view thereof;
FIG. 5 is a left side elevation view thereof; and
FIG. 6 is a right side elevation view thereof.

FIG. 5

FIG. 6
